UNITED STATES PATENT OFFICE.

GEORGE GILL, OF TAUNTON, MASSACHUSETTS, ASSIGNOR TO REED AND BARTON, OF SAME PLACE.

DESIGN FOR CAKE-HOLDERS.

Specification forming part of Design No. 6,799, dated August 12, 1873; application filed June 25, 1873.

To all whom it may concern:

Be it known that I, GEORGE GILL, of Taunton, in the county of Bristol and State of Massachusetts, have invented a new and original Design for a Cake-Holder; and I do hereby declare the following to be a full, clear, and exact description of the same, reference being had to the accompanying drawing forming a part of this specification, in which—

Figure 1 is a front elevation, and Fig. 2 is a top view.

The nature of my design is fully illustrated in the drawing to which reference is made.

In the drawing, A is the cake-holder, which is provided with the ball B, having a circumjacent central and vertically-fluted band, b. This is placed upon the apex of a curved oblong pillar plate, C, whose long ends c c are spread to afford an apparently substantial base. In the space inclosed by this vertical pillar-plate is located an erect female figure, D, standing upon a pediment, d, and having the junction of her lower limbs modestly covered with leaves, while the rest of her person is nude. Her right arm is held out from side, and the right hand clasps a garment that protects from view the rear of her person, while the left arm is held aloft, and the left hand made to touch the trimming with which her hair is adorned. E is the basis whereon rests

the lower ends of plate C and the pediment d. This base is provided with four feet, above each of which peers a man's face and head. F F are two similar ornamental attachments consisting of three inwardly concaved leaves, whose stems are conjoined, and apparently held on each side by fluted clamps, each having a trifoliar termination. Each of these is placed at one oblong end of the cake-holder A, while the handle G is pivoted across the transverse diameter.

Having thus described our invention, what we claim as new, and desire to secure by Letters Patent, is—

1. The two ornamental attachments F F placed on opposite sides of the cake-holder, as shown and described.
2. The pillar-plate C arranged with or without the female figure in the inclosed space, and surmounted by the ball B on which rests the cake-holder.
3. The design of the female figure standing upon the pediment with one hand by her side and the other held overhead, as shown and described.

GEORGE GILL.
